UNITED STATES PATENT OFFICE.

THOMAS S. COOKE, OF WHITING, INDIANA, ASSIGNOR TO STANDARD OIL COMPANY, OF CHICAGO, ILLINOIS, A CORPORATION OF INDIANA.

ART OF PETROLEUM DISTILLATION.

Application filed February 23, 1918. Serial No. 218,716.

To all whom it may concern:

Be it known that I, THOMAS S. COOKE, a citizen of the United States, residing at Whiting, in the county of Lake and State of Indiana, have invented a new and useful Improvement in the Art of Petroleum Distillation, of which the following is a specification.

My invention relates to the art of petroleum distillation and will be full understood from the following specification.

In the fractional distillation of crude petroleum as ordinarily practised at the present time there is produced a cut or fraction intermediate gasoline and kerosene, or between "naphtha" and "refined oil", following the more common usage of the art. This intermediate cut has little or no recognized place in the petroleum products market, being produced not by design or intent but as a necessary result of the imperfect fractionation obtained in the ordinary crude still. In general it may be said to consist of a mixture of approximately equal parts of hydrocarbons boiling above and below the dividing line (or middle point of lap or gap) between naphtha and refined oil.

At an earlier stage of the industry this intermediate fraction was refractionated more or less perfectly by the direct vaporizing action of steam in stills specially constructed for that purpose and commonly known as "steam stills", by reason of which treatment the stock or cut in question received in many refineries the name "steam still stock". Probably because of the waste of heat by this method, steam distillation of the cut or stock referred to has now been largely replaced by continuous distillation in fire stills.

My invention particularly relates to improvements in such continuous distillation of the stock or cut referred to, the character and origin of which will, it is believed, be clear to those skilled in the art from the foregoing brief description, it being understood that while the terminology employed herein may be susceptible of other interpretations, it is used in the following specification in the sense defined above.

For the practise of my invention I em-

ploy a continuous distilling apparatus of the character illustrated diagrammatically in the accompanying drawings. In these drawings—

Fig. 1 is a front elevation, partly in section, of a battery of stills.

Fig. 2 is a top plan view.

Fig. 3 is a side elevation, and

Fig. 4 is a longitudinal central section through one of the vapor heat exchangers, taken on the line 4 of Fig. 2.

Referring more particularly to the drawings, the four stills which make up the battery illustrated are designated 10 to 13, each still being mounted upon its own setting (the settings shown being for stoker-fired furnaces). By the stepped arrangement of the settings the stills are carried at progressively lower levels from left to right of the series, which, in combination with the constant-level overflow connections 14 which join each higher still with the next lower still, makes it possible to feed the stock under treatment into the highest still only and permit it to flow continuously through the series to the lowest still undergoing distillation in each of the four stills for an approximately equal period of time. This arrangement and manner of operating the stills themselves is so well understood in the art as to require no further description.

The first two stills of the series, i. e., stills 10 and 11 are each provided with a fractionating column of the bubbling-pan type designated 15. As shown in the sectional view (Fig. 1) the column consists of a cylindrical casing, which will preferably be lagged, within which is mounted a series of horizontal partitions in the form of pans 16. Each pan has communication with the vapor space above the next lower pan through a plurality of capped nipples, the caps 17 of which extend below the normal liquid level in the pan to form a liquid seal through which the outgoing vapors must bubble. A constant level is maintained in each pan through an overflow pipe 18 which extends well below the normal liquid level in the next lower pan.

From the top of each column two vapor lines 19 lead to the inlet chamber 20 of a

- horizontal tubular vapor heat exchanger 21, the construction of which is shown in Fig. 4. As is there illustrated, the vapor tubes are arranged in two sets, a forward set 22 and a rear set 23, separated by a vapor-chamber 24, a third vapor chamber 25 being provided in the rearward end of the cylinder. From each of the three vapor chambers there is led a valved drip connection 26, the three connections joining a common drain line 27 which connects at its forward and rearward ends respectively with the column 15 and the final condenser 26^a (Fig. 3). Four block valves 27¹ in the drain line make it possible to direct the condensate from the three vapor chambers back to the column 15 or to the final condenser 26^a, or partly to one and partly to the other, as desired.
- From the last vapor chamber 25 of the heat exchanger a vapor line 28 leads to the final condenser 26^a referred to, this being a water-cooled condenser of ordinary form having a tail-pipe 29 and gas pipe 30, either or both of which may be manifolded for any number of stills.

The overhead construction described above is common to all of the stills of the battery, save for the omission of the columns 15 on the last two stills, i. e., stills 12 and 13. In place of the columns, these stills have only relatively small domes 31 to which the vapor lines are directly connected. By reason of the omission of the columns the vapor heat exchangers of these stills may be mounted lower, as shown in Fig. 1.

It is the purpose of the vapor heat exchangers to transfer the heat of the outgoing vapors to the incoming feed stock. This result is effected by passing this stock through the spaces surrounding the vapor tubes. The incoming stock enters the rear of the exchanger of the first still 10 by a pipe 32, passes over the rear bank of tubes, is transferred around the middle chamber 24 by a bypass 33, and after passing over the front tube-bank is carried by a cross-connection 34 to the next exchanger, through which it follows the same course and thus progressively through the battery. From the last exchanger the heated feed stock is led through a line 35 to the still 10. The course of the oil through the stills has been heretofore described. From the last still the residue or tar is withdrawn by an overflow connection similar to the connection between the stills.

The process of distillation as carried out in the above described apparatus in accordance with my invention is as follows: A typical "steam still stock" is introduced through the feed line 32, traverses the heat exchangers as described, enters the still 10 in a heated condition and passes through the series of stills undergoing distillation in

each still to an approximately equal extent. A tar or residue comprising approximately 10% of the volume of the stock fed in will be continuously withdrawn from the last still 13. Each of the four stills of the series represented, therefore, will accomplish the distillation of 20%-25% of the stock charged.

By way of example, a stock of this character may be said to have an initial boiling point of approximately 290° F. and a maximum boiling point (98% off) of 570° F. In the operation of the apparatus described, this stock will produce two distillates, a naphtha distillate and a refined oil distillate, the first of which will be obtained by mixing the condensate from the stills 10 and 11, and the second from the stills 12 and 13. The naphtha distillate may, with careful operation, show an initial boiling point of 430° F. and a maximum boiling point of 480° F., while the refined oil distillate will have an initial boiling point of 440° F. and a maximum boiling point of 550° F., the two fractions, refined oil and naphtha, being obtained in approximately equal proportions.

It will be observed from the foregoing example of operation that it is possible by the practice of my invention to actually produce a distinct gap between the maximum boiling point of the naphtha cut and the initial boiling point of the refined oil cut, indicating a very perfect separation and the production of a maximum yield of the relatively valuable naphtha.

In contra-distinction to the relatively perfect separation exemplified by the foregoing, is the ordinary imperfect separation commonly effected by continuous distillation, even where the number of stills in the battery is very great. For example, in a battery of seven stills of the same general type as the stills 12 and 13, illustrated in the drawing, a stock of the characteristics described produces a naphtha cut from the first three stills having an initial boiling point of 265 and a final boiling point of 420; and a refined oil cut from the last three stills having an initial boiling point of 355 and a final boiling point of 570, with 35% boiling below 420° F. In place of the 10° gap in boiling points attainable by the practice of my invention, it therefore appears that with regard to the first and last three stills alone, and excluding the center still, it is impossible to produce a separation at all comparable with that obtainable by my invention. The distillate from the fourth or middle still of the series of seven referred to showed an initial boiling point of 320 and a maximum boiling point of 500, consisting of approximately 65% naphtha and 35% refined oil. This distillate from the fourth still, therefore, was very little different from the charging stock itself, and

since it was available neither for naphtha or refined oil, it was necessarily returned for re-distillation.

I attribute the success of my improved 5 method of distillation to the action of the bubbling-pan fractionating columns 15, which act to accurately separate from the mixed vapors passing from the stills 10 and 11 those fractions thereof which properly 10 belong in the naphtha cut, returning to the stills the fractions which belong to the refined oil cut.

Although it has heretofore been proposed 15 to employ fractionating columns in connection with the distillation of petroleum oils, I am not aware that any method has heretofore been devised for taking advantage of the possibilities of the fractionating columns in a commercially feasible manner as 20 is herein suggested, i. e., by providing a series of stills equipped with such columns through which series the oil under treatment is continuously passed. By this method of operation the inherent difficulties with and 25 objections to the use of fractionating columns for producing the common commercial petroleum products is overcome.

For simplicity of illustration I have shown a battery comprising only four stills. 30 I prefer, however, to use a much larger number of stills, for example, six to ten stills in each battery, and where the charging stock or mixture to be fractionated comprises approximately equal proportions of 35 the two commercial cuts, as in the "steam still stock" taken by way of example herein, the proportion between the number of stills equipped with fractionating columns and the number of simple stills should remain 40 approximately as given, i. e., equal numbers of the two varieties of stills. If, on the other hand, the proportion of lighter constituents which it was desired to fractionate from the charging stock were smaller, then 45 the number of the stills in the battery which were required to be equipped with the fractionating columns might be proportionately reduced. In general, therefore, it may be said that my invention contemplates the use 50 of a battery of continuous stills having those stills from which the lighter cut or cuts are to be taken equipped with fractionating columns, while that still or stills from which the heaviest cut is taken are not so equipped.

55 While I have shown and described in detail one specific apparatus in accordance with my invention, and the exact manner in which the distillation should be carried out therein with a particular charging stock, 60 it is to be understood that this is illustrative only, and for the purpose of making the invention more clear, and that the invention is not limited to these details nor to any of them, except in so far as they are set forth in the following claims, in which it is my in-

tention to claim all novelty inherent in my invention as broadly as is permissible in view of the prior art.

What I claim is:

1. The method of distilling a petroleum 70 oil, comprising a mixture of fractions having a relatively wide range of boiling points, which consists in passing such oil in a continuous stream through a series of stills maintained at increasing temperatures in 75 the direction of flow of the oil, subjecting all of the vapors passing from each still to the action of a fractionating column, whereby all vapors condensing below a predetermined temperature are condensed in said 80 columns, refluxing to the stills the vapors condensing in their respective columns in counter-current to the vapors issuing from said stills, and separately condensing and collecting the vapors which escape condensation in the columns, whereby there is obtained from the oil in a single distillation 85 a maximum yield of distillate having a minimum end boiling point.

2. The method of distilling petroleum oil 90 made up of fractions having a relatively wide range of boiling points, which consists in passing such oil through a series of continuous stills, each of which is equipped with a fractionating column, and mixing the distillates from said stills to produce a cut having a maximum boiling point not substantially overlapping the initial boiling point of the residue of the oil under treatment. 100

3. The method of distilling petroleum oils, comprising fractions having a relatively wide range of boiling points, which consists in passing said oil through a series of continuous stills, the stills at the incoming end of the said series being equipped with fractionating columns, while the stills at the outgoing end are not so equipped, blending the distillates from such first-named stills to produce a cut lighter than 105 the oil under treatment and having a narrower range of boiling points, and blending the distillates from the other stills of the battery to produce a cut heavier than the oil under treatment and having a narrower 110 range of boiling points, whereby the maximum boiling point of the lighter cut may be maintained substantially at or below the initial boiling point of the heavier cut. 115

4. The method of distilling steam still 120 stock, which consists in feeding such stock through a battery of continuous stills in which the stills at the incoming end of the battery are equipped with fractionating columns while the stills at the outgoing end of the battery are not so equipped, blending the distillates from the fractionating column stills to produce a naphtha cut, and blending the distillates from the other stills to produce a refined oil cut, the operation 125 130

being conducted so as to avoid substantial lap in boiling points of the cuts.

5. The improvement in the art of fractionating petroleum oil products having a continuous range of boiling points, which consists in distilling off a part of said oil, at least, through a reflux fractionating column, returning to the distilling body of oil only condensate formed in said column

10 in counter-current to the vapors issuing from the still and continuing such distillation until the condensate from the vapors issuing from said column has a desired end boiling point whereby a residue is formed

15 in said still having an initial boiling point substantially higher than the end boiling point of said condensate.

6. The improvement in the method of fractionating a petroleum oil of the gasoline-kerosene range of boiling points, which consists in distilling off the gasoline fractions of such oil through a reflux fractionat-

ing column, returning to the distilling body of oil only condensates formed in said column in counter-current to the vapors 25 issuing from the still, and controlling the distillation to produce a liquid distillate passing the column and having a desired end boiling point, thereby producing a kerosene residue having an initial boiling 30 point substantially above the end boiling point of said distillate.

7. The improvement in the method of fractionating a petroleum oil of the gasoline-kerosene range of boiling points, which 35 consists in distilling off the gasoline fractions of such oil through a fractionating column, the condensing zones of which are maintained at such temperatures as to produce a gasoline distillate having an end 40 boiling point substantially lower than the initial boiling point of the undistilled kerosene residue.

THOMAS S. COOKE.
